UNITED STATES PATENT OFFICE.

JULIUS DUNNER, OF BROOKLYN, NEW YORK.

HAIR-COMB.

1,311,330.

Specification of Letters Patent. Patented July 29, 1919.

Application filed September 11, 1918. Serial No. 253,618.

To all whom it may concern:

Be it known that I, JULIUS DUNNER, a Russian now residing in the United States, residing at Brooklyn, in the county of Kings and State of New York, have invented new and useful Improvements in Hair-Combs, of which the following is a specification.

This invention relates to new and useful improvements in hair-combs, and a principal object of the same is the provision of a sanitary hair-comb having parts made and assembled in such manner that the teeth may be entirely removed for thorough cleaning, and that if any of the teeth become damaged or broken, new teeth may be readily installed.

Another object of the invention is the provision of a comb of this character embodying features of adjustment, which permit the employment of either relatively fine or coarse teeth, the same making provision also for securing the teeth in position with either relatively narrow or wide spaces intervening therebetween.

A still further object of the invention is the provision of a construction involving features of the character specified, which may be employed in providing combs equipped with teeth pointed for use on both extremities, or at one extremity only.

With the foregoing objects in view and others, the invention resides in the details of construction and in the arrangement and combination of parts hereinafter described, defined in the claim, and illustrated in the accompanying drawings, forming a material part of this specification; and it will be understood that changes and alterations in the precise details of construction as herein disclosed, may be made, to which changes and alterations the inventor is entitled, provided the same are effected within the scope of what is claimed.

In the accompanying drawings:—

Figure 1 is a view in perspective of a comb made in accordance with my invention.

Fig. 2 is a side elevational view of the same, parts being broken away.

Fig. 3 is a view in edge elevation.

Fig. 4 is a view in end elevation.

Figs. 5, 6 and 7 are detail views.

Fig. 8 is a side elevation of the comb form.

Fig. 9 is a side elevational view of another form, fragmentally shown.

Fig. 10 is an end elevation of the comb shown in Fig. 9.

Fig. 11 is a cross sectional view, taken on the line 11—11 of Fig. 9.

With more particular reference to the accompanying drawings, the numerals 12 and 13 represent back or casing sections, made from rubber, bone, aluminum or other suitable material from which the backs of combs are usually made. These sections are made preferably rectangular in form, are of the same size and shape, but one of them, herein shown as 12, is formed along one end with a lateral flange 14, which projects for a distance approximately equal to the body width of the teeth to be employed.

At one end the section 13 is removably secured flat upon the flange 14, by means of screws 15 or equivalent means; and at the opposite end, it is similarly secured together with an interposed end tooth 16, upon the section 12. The body part of the end tooth 16 corresponds as to width, with the flange 14, while the extremities of the same extend beyond the opposite edges of the sections 12 and 13 and are shaped to provide the usual 80 combing points 17.

To one of the sections, preferably section 12, as herein shown, there is riveted longitudinally and centrally thereof, a tooth retaining strip or rib 18, the thickness of which is preferably about one-half of the width of the flange 14 and incidentally of the body portions of the teeth. Mounted upon this retaining strip 18 is an end retaining tooth 19, which corresponds with the opposite end retaining tooth 16, and also a series of teeth 20, the said end retaining tooth 19 as well as said teeth 20 being all provided for the purpose midway their length with transverse notches or recesses as 21 so as to fit upon the said rib. These teeth 20 are thus mounted upon the retaining strip between the end retaining teeth 16 and 19, so that when the section 13 is applied, the same will be held securely together with the tooth 19, for movement longitudinally thereof.

It is essential that the body portions of the teeth 20 be formed with flat sides or faces as 22 and with parallel edges as 23, so as to be arranged in series upon the strip 18, each tooth being maintained flat against its neighbor, or held spaced therefrom by means of a spacer as 24, which is also suitably notched or recessed midway its length 110 to slidably fit upon the retaining strip. The length of the spacers 24 preferably equals

that of the body portions of the teeth in order to properly brace the teeth with respect to each other. The outer portions of the teeth 20 beyond the opposite edges of the sections are beveled or curved in any suitable manner to provide the necessary service or combing points 25. The teeth 20 may be either relatively thick or thin having either relatively coarse or fine combing ends 10 as desired; and likewise the spacers 24 may be relatively thick or thin to hold the teeth spaced from each other as desired. By varying the size of the teeth and of the spacers therefor, the comb may be made either coarse or fine, or even one portion thereof may be made coarse while the other portion is made fine.

Threaded through the flange 14 are the set screws 26 arranged preferably one on 20 each side of the location of the retaining strip 18. By turning these set screws, the teeth may be either locked upon the retaining strip or released for removal.

In Figs. 9, 10 and 11, I illustrate another 25 form, the construction and assembly whereof are precisely the same as above described, excepting that the sections 27 and 28 are preferably made of less width than the sections 12 and 13, and that the end retaining

teeth 29 and 30, as well as the intermediary 30 teeth 31, have combing points on only one side of the sections, the opposite extremities of the same terminating flush with the edges of the sections.

Having thus described my invention, 35 what I claim is:—

In a comb of the class described, a pair of rectangular backing sections, connections between the opposite ends of the sections for holding them in confronting spaced 40 relation, one connection consisting of an end flange formed integral with a section and the other of a fixed end tooth, a strip carried by one of the sections between said end flange and said end tooth, a series of teeth 45 notched between their ends to slidably fit on said retaining strip and projecting beyond the sections, one of said teeth representing an end tooth which comes adjacent to said end flange, and means associated 50 with said end flange and adapted to act on the last-mentioned end tooth for clamping the series of teeth rigidly between the last-mentioned end tooth and said fixed tooth.

In testimony whereof I have signed my 55 name to this specification.

JULIUS DUNNER.

Copies of this patent may be obtained for five cents each, by addressing the "Commissioner of Patents, Washington, D. C."
